[57] **CLAIM**

The ornamental design for a broadcast spreader, as shown and described.

DESCRIPTION

FIG. 1 is a perspective view of a broadcast spreader embodying my new design, the perspective looking down on the front and right side thereof;

FIG. 2 is a right side elevational view thereof;

FIG. 3 is a left side elevational view thereof;

FIG. 4 is a front elevational view thereof;

FIG. 5 is a rear elevational view thereof;

FIG. 6 is a top plan view thereof;

FIG. 7 is a bottom plan view thereof; and,

FIG. 8 is a view similar to FIG. 2 showing the broadcast spreader in a folded storage or transporting position.
